UNITED STATES PATENT OFFICE.

JOSEPH G. MACE, OF HUDSON, MASSACHUSETTS.

BOTTLE.

SPECIFICATION forming part of Letters Patent No. 623,679, dated April 25, 1899.

Application filed October 18, 1898. Serial No. 693,851. (No model.)

To all whom it may concern:

Be it known that I, JOSEPH G. MACE, a subject of Victoria, Queen of Great Britain, residing at Hudson, in the county of Middlesex 5 and State of Massachusetts, have invented a new and useful Improvement in Bottles, of which the following is a full, clear, and exact description, reference being had to the accompanying drawings, forming a part of this specification, in explaining its nature.

The invention relates to devices hereinafter described for indicating the reuse of bottles, jugs, and other vessels. It is represented in the drawings as applied to a bottle.

15 It comprises a cylindrical case having a passage through which the contents of the bottle may be removed, a peculiar valve and valve-holder, and means for permanently attaching it to the neck of a bottle after the 20 valve has been set against its seat to close the passage in the case.

It further relates to means whereby the valve may not be restored to its seat after the cylinder has been attached to the bottle and 25 the valve released to permit the removal of the original contents of the bottle.

In the drawings, Figure 1 is a view in vertical section of the neck of a bottle containing my improvement. Fig. 2 is a view in section of the neck of the bottle prepared to receive my improvement. Fig. 3 is a view in plan of the complete bottle of Fig. 1. Fig. 4 is a view in cross-section upon the dotted line 44 of Fig. 1, representing also the parts above 30 said line. Fig. 5 is a view in section upon the dotted line 55 of Fig. 1. Fig. 6 is a view representing the valve-casing and parts before they are assembled together. Fig. 7 is a view of a modified form of the bottle-neck, 35 to which reference is hereinafter made.

40 Referring to the drawings, A represents the neck of the bottle. It is provided with the shoulder a in its passage a', adjacent to the top edge a² of the neck. This shoulder is about the lower edge of a continuous inward 45 extension a³ and serves to receive and hold the ends of the fastening-springs b, which fasten the cylindrical valve-case B in the neck of the bottle. The inward extension a³ 50 reduces the size of the passage a' of the bottle to the bore of the valve-case B, which is made to fit the same.

The valve-case is preferably of metal and is cylindrical throughout, excepting that at its upper end it has an outward-extending flange 55 b'. There extends through the valve-case from one end to the other a passage b². The lower end b³ of the valve-case is enlarged to the shoulder b⁴, and there is arranged to bear against the shoulder an elastic seat b⁵, of rubber or other similar resilient material.

The chamber b³ is of a size to receive the ball-valve C, and this ball-valve is secured to the cylindrical case B before it is attached to the bottle and when it is possible to bring 65 sufficient pressure against it to compress the valve-seat b⁵ enough to permit the end d of the holding-rod D to make engagement with the ball, such engagement being possible when the ball is pressed hard enough against 70 the packing to compress it, but being otherwise impossible—that is, the weight of the ball alone on the packing or the weight of the ball plus the weight of the contents of the bottle being insufficient to compress the 75 packing or seat to an extent necessary to permit the said engagement to be made. I prefer for the purpose of making engagement to provide the ball with a small screw-threaded holder D screw-threaded to fit the threaded hole and to engage the holder and the ball by turning the ball or the holder sufficiently to cause the threads to slightly lap, perhaps a quarter or a third of a revolution. The 80 holding-rod is held at the outer end of the case by a key d², by means of which it may be turned to release the ball. This holder has a short cylindrical section d³, which extends into the passage b² enough to steady it, 85 and it may also have the holes d⁴, through which the passage b² may be seen.

The springs b' are attached to the outer side of the case near its inner end, and their free ends extend outwardly therefrom. (See 95 Fig. 6.) The cylindrical case thus prepared and closed is then inserted into the neck of a filled bottle, a packing e, of rubber or other resilient material, being first placed to be interposed between the flange and the top surface of the neck. The ends of the springs b' are so arranged in relation to the flange b' as to require the compression of the packing e 100 before the ends of the springs will clear the

shoulders a and spring to a position to engage the same, as represented in Fig. 1. The surface of the case may have recesses b^6 of the size of the springs b to receive them as the portion of the case against which they are is being moved through the section a^3 .

The valve-seat b^5 and valve C prevent the escape of the contents of the bottle through the passage b^2 until the valve is released by the turning of the holder D , and when released the valve cannot be returned to its holder because the valve-seat, having been released, expands and serves to hold the valve away from the holder.

15 It will be understood that the holder is not made long enough to permit an engagement between its end and the valve to be made excepting when the valve-seat has been compressed.

20 It will further be seen that the closed valve-case cannot be removed from the neck of the bottle once inserted therein without breaking the bottle.

25 It will also be seen that the packing between the flange b' and the end of the neck acts to prevent the escape of the contents of the bottle between the casing and the neck and also serves to continuously hold the ends of the spring-arms against the shoulder, and 30 thus not only prevents rattle, but also acts as a means for overcoming any slight inequalities in the length of the thickened end or section a^3 .

35 In Fig. 7 I have represented the bottle-neck as not only provided with a shoulder for receiving the ends of the valve-case holders, but as also drawn in slightly, so as to come into contact or very nearly come into contact with the lower edge of the valve-case, and 40 thus close the space surrounding the lower end of the valve-case, as represented in Fig. 1. This construction has an advantage of a negative character perhaps in that it removes any suggestion as to the possibility of a restoration of the valve to its valve-seat by any device which should use said recess as a means for accomplishing this end.

Having thus fully described my invention, I claim and desire to secure by Letters Patent 50 of the United States—

1. In a bottle the combination of the bottle-neck having a valve-case-receiving section and a shoulder below said section of the valve-case having at its outer end a flange

and at its inner end a chamber b^3 , the compressible valve-seat, a valve to compress the valve-seat and to hold it compressed by engaging means which make engagement therewith when the valve-seat is compressed, but which cannot make engagement therewith when the valve-seat is uncompressed, said engaging means, automatic spring-locks carried by the case to engage the shoulders of the bottle-neck and a compressible packing between the case-flange and the upper end of the bottle-neck.

2. In a bottle a valve-case having an opening through which the contents of the bottle may be removed, a compressed resilient valve-seat, a valve held against said compressed resilient seat by devices which engage the valve when so held but which cannot engage said valve when the packing is uncompressed, and which devices are actuated to release the valve from the exposed end of the case, the 75 said seat being compressed by the valve and the valve being secured to said holding device before the casing is attached to the bottle and means for attaching said casing to the bottle.

3. A bottle having a compressed resilient valve-seat surrounding the passage from the bottle, a valve to compress said seat, means for holding said valve to compress said seat and for releasing the said valve, which means 85 may not make engaging connection with said valve after it has been released because of the expanding of the compressed valve-seat to its original size.

4. A bottle having a neck provided with a shoulder and an enlargement beneath said shoulder, a valve-case to fit the neck of the bottle having a flange at its upper end to bear against the end of the neck, also extended in the neck of the bottle to said enlargement, 95 locking means to engage said shoulder, a compressible valve-seat in said case surrounding the passage from the bottle, a valve to compress said seat, means for holding said valve to compress said seat and for releasing said valve, which means may not make engaging connection with said valve after it has been released because of the expansion of the valve-seat to its original size.

JOSEPH G. MACE.
